UNITED STATES PATENT OFFICE.

ALFRED WALDEN, OF LONDON, ENGLAND, ASSIGNOR OF ONE-HALF TO HARRY JOSEPH WALSH, OF BEXHILL-ON-SEA, ENGLAND.

CONSTRUCTION OF HAMPERS.

1,327,362.

Specification of Letters Patent.

Patented Jan. 6, 1920.

Application filed November 15, 1917, Serial No. 202,150. Renewed November 20, 1919. Serial No. 339,316.

To all whom it may concern:

Be it known that I, ALFRED WALDEN, a subject of the King of Great Britain, residing at London, in the county of Middlesex and country of England, have invented certain new and useful Improvements in the Construction of Hampers, of which the following is a specification, reference being had therein to the accompanying drawing.

10 This invention relates to the construction of hampers, baskets or the like and has for its object to increase the strength thereof.

In practice hampers have been constructed with the basket work sides built into side plates or battens at the bottom, this construction having been successful in practice, except for a weakness at the ends of the hamper.

The present invention aims to improve the former constructions by providing special stout strengthening canes running parallel with the side plates and extending entirely around the ends of the hamper. These strengthening canes may be arranged in pairs interlaced across the bottom of the hamper and being extended up at each end thereof, the ends being finished at the top edges of the hamper in any desired manner.

A further object of the invention is to improve the method of securing side canes to the side plates. The construction shown provides holes in these side plates drilled in opposite directions in the two halves of the side plates, the canes being inserted in these holes.

Referring to the drawings, Figure 1 is a perspective view of a part of a hamper, the view being taken during the construction of the hamper;

40 Fig. 2 is a sectional view through one of the side plates showing a supporting roller which may be employed;

Fig. 3 is an enlarged perspective view of one of the side plates showing some of the vertical canes in position and also showing a slightly modified form of the side plate; and

Fig. 4 is a sectional view longitudinally of Fig. 3.

50 In the drawings the hamper is shown as provided with side plates or battens 1 and cross canes 2 to connect these side plates together, the battens being spaced apart and rigidly secured one to the other by a brace

1^a and a tie rod 12. These canes extend 55 across the space between the side plates and are inserted in holes in the inner sides of the plates. The vertical canes 3 are inserted in holes 4 in the side plates, the holes in half of the side plate being arranged in opposite 60 directions from those of the other half. The two holes nearest the center of each plate marked 4^a thus communicate with each other so that the particular vertical canes 3 entering these two holes, which are marked 65 with the numeral 5, wedge tightly together when they are pressed in place. This appears clearly in Fig. 3 and the oblique slope of the slots 4 is shown in Fig. 4.

To strengthen the end walls and the bottom of the hamper strengthening canes 6 are employed. These consist each of a single length running entirely across the bottom parallel to the side plates and being wound, as at 8, completely around the end 70 cross canes and then carried up the side of the hamper to the top. These strengthening canes are shown as in pairs and are interlaced with the cross canes 2. Additional vertical canes at the ends of the hamper are 75 shown and these may be strong canes like the strengthening canes 6 and are fastened to the end cross canes 7 as by cords 15.

The basket is completed by interlacing canes 16 with the strengthening canes 6 and 80 the side canes 3 in any desired manner and to add stiffness to the hamper a cross bolt 12 passing through the side plates may be employed.

To permit easy movement of the hamper 90 the side plates may be provided with angle metal pieces 10 and passing through these metal pieces may be a pin or rod 11 on which a roller 9 is mounted. This roller turns inside the angled piece 10 and permits easy 95 movement of the hamper.

Fig. 1 shows metal plates 13 surrounding the ends of the side plates so as to prevent injury to the hamper if it is moved into some other article and Fig. 3 shows a slightly 100 different form of such plates marked with numeral 13^a.

It will be seen that the construction provides a strong hamper, the provision of the strengthening canes 6 and the side canes 3 105 particularly aiding in stiffening the hamper and preventing weakness thereof, especially at the ends. Although primarily intended

for hamper construction the invention may be found advantageous in the construction of other basket work, such for example as basket work chairs or the like, where the 5 basket work is built up from a wooden frame.

A prior British patent to the present inventor, No. 2639 of 1906, shows a basket of the general type herein disclosed, and the 10 principal improvement in the present construction lies in the addition of the strengthening canes 6. These have been found to add greatly to the strength and wearing qualities of the hamper.

15 Having thus fully described my invention, what I claim as new and desire to secure by Letters Patent, is:—

1. In a hamper the combination with two parallel supporting plates spaced apart and 20 rigidly secured one to the other, cross canes extending between the supporting plates and having their ends secured therein, vertical canes secured to the end cross canes and extending to the top of the hamper, strengthening 25 canes of single lengths arranged in pairs alternating with said vertical canes and interwoven with the cross canes, extending parallel to the side plates, wound around the end cross canes and extending 30 up the sides to the top of the hamper.

2. In a hamper the combination with two parallel supporting plates spaced apart and rigidly secured one to the other, cross canes extending between the supporting plates and 35 having their ends secured therein, vertical canes secured to the end cross canes and extending to the top of the hamper, strengthening canes of single lengths alternating with said vertical canes and interwoven with the cross canes, extending parallel to the side plates, wound around the end cross canes and extending 40 up the sides to the top of the hamper.

3. In a hamper the combination with two 45 parallel supporting plates spaced apart and rigidly secured one to the other, cross canes extending between the supporting plates and having their ends secured therein, vertical canes secured to the end cross canes and extending 50 to the top of the hamper, strengthening canes alternating with said vertical canes, extending parallel to the side plates, wound around the end cross canes and ex-

tending up the sides to the top of the hamper.

4. In a hamper the combination with two parallel supporting plates spaced apart and rigidly secured one to the other, cross canes extending between the supporting plates and 60 having their ends secured therein, vertical canes secured to the end cross canes and extending to the top of the hamper, strengthening canes alternating with said vertical canes, interwoven with the cross canes and extending up the sides to the top of the 65 hamper.

5. In a hamper the combination with two parallel supporting plates spaced apart and rigidly secured one to the other, cross canes extending between the supporting plates and 70 having their ends secured therein, vertical canes secured to the end cross canes and extending to the top of the hamper, strengthening canes arranged in pairs alternating with said vertical canes, interwoven with the 75 cross canes and extending up the sides to the top of the hamper.

6. In a hamper the combination with two parallel supporting plates spaced apart and rigidly secured one to the other, cross canes 80 extending between the supporting plates and having their ends secured therein, vertical canes secured to the end cross canes and extending to the top of the hamper, strengthening canes arranged in pairs alternating with said vertical canes, wound around the 85 end cross canes and extending up the sides to the top of the hamper.

7. In a hamper the combination with a bottom comprising cross canes, vertical canes 90 secured to the end cross canes and extending to the top of the hamper, strengthening canes arranged in pairs interwoven with the cross canes, alternating between the vertical canes and extending up the sides to the top 95 of the hamper.

8. In a hamper the combination with a bottom comprising cross canes, vertical canes secured to the end cross canes and extending to the top of the hamper, strengthening 100 canes interwoven with the cross canes, alternating between the vertical canes and extending up the sides to the top of the hamper.

In testimony whereof, I affix my signature. 105
ALFRED WALDEN.
